ATTORNEY

UNITED STATES PATENT OFFICE

NICOLAS PANZIREFF, OF MOSCOW, RUSSIA

DRIER

Application filed December 5, 1928, Serial No. 323,987, and in Germany March 21, 1928.

My invention relates to driers and has a particular reference to driers of a conveyer type adapted to dry granular matter or, with some modifications, liquid or semiliquid materials.

The object of my invention is to provide a drier of a continuous type, adapted to receive material at one end and to continuously discharge it at the other, with a provision to periodically stir the material which is being dried, so as to uniformly expose all the individual particles to the action of the drying air.

I also provide an improved air circulating system so as to obtain a uniform air flow in different portions of the drier, the air being circulated repeatedly over the material so that it becomes fully saturated with moisture before it is finally exhausted.

My invention is more fully described in the accompanying specification and drawing in which—

Fig. 1 is a sectional elevation of my drier,
Fig. 2 is a vertical cross-section of same,

Fig. 3 is a plan view of the bottom air ducts,

Fig. 4 is a diagrammatic view of the drier in a state for drying semi-liquid materials.

Fig. 5 is a top view of the conveyor,
Fig. 6 is a partial view of the conveyor and conveyor sprocket wheel, when corresponding to Figs. 1-3, and

Fig. 7 is a similar view of the conveyor, when corresponding to Fig. 5.

My drier consists of a chamber 1 made preferably of metal and lined inside with a refractory or heat insulating material 2. A plurality of endless conveyor chains 3 are placed inside of the chamber 1 on sprockets 4 mounted on shafts 5 extending between the walls of the drier and provided with external or driving sprockets 6 connected together with chains 7 operated by a suitable motor (not shown) or other source of power. Each shaft supports two (or more) pairs of sprockets 4, and the corresponding chains of each pair of sprockets are connected together with cross shafts 8 attached to the links of the chains. Conveyor plates or trays 9 are mounted rotatively on the cross shafts 8 and

are supported in a horizontal position by means of guiding bars 10 supported on transversely placed beams 11. The conveyors in each vertical row are substantially alike and are driven at the same speed, although it is possible to vary the speeds of different conveyors by using sprockets 6 of different sizes, in order to obtain a uniform rate of drying on successive conveyors.

A hopper 12 is placed above each top conveyor and is provided with a feeding mechanism (not shown) of any ordinary type adapted to deliver material on the conveyor at a uniform rate.

The plates 9, sliding on the guiding bars 10, represent a flat conveyor surface adapted to receive the material from the hopper 12, at the end of the conveyor, at a certain distance from the sprocket 9, the guiding bar 10 is terminated, its end being bent down as shown in Figs. 1 and 6. Without support from the bar the plates 9 hang vertically. For the lower or return portion of the conveyor a second or lower guiding bar 13 is provided. At the incoming end it extends farther than the corresponding bar 10 above causing the plates 9 to take a horizontal position at the point where the upper plates 9 already hang vertically. This arrangement is shown in Fig. 1 at the right hand end, the movement of the conveyors being indicated with arrows 14 and 15. At the other end of the conveyor the bar 13 ends at a certain distance from the sprocket, allowing the plates 9 to hang vertically before they reach the sprocket.

The next conveyor below has an identical arrangement, the bar 10 extending to the left farther than the bar 13 above so as to form a flat receiving surface from the plates 9 at the point where the plates of the upper conveyor already hang vertically.

The conveyors being all alike it is evident that any number of them may be arranged vertically, according to the capacity required and the time of drying.

The conveyors 9 for drying material are arranged in units there being shown two such units in Fig. 2. Between the units at the bottom of the drier chamber a tunnel or duct 17 is provided. It has a slot 18 on top and a

horizontal bottom wall 18' and is connected with a pipe or flue 19 through which hot air is admitted. The roof of the drier has cylindrical vaults 20 over each conveyor unit in order to facilitate the circulation of air. Return ducts or tunnels 21 are provided at the bottom of the drier near the side walls of it. They have longitudinal slots 22 and are in communication with an exhaust pipe 23.

10 The slot 18 is made of a gradually enlarged width, having its narrow end at the point where the hot air enters the tunnel 17. The slots 22 are made narrower at the exhaust end near the pipes 23.

15 Instead of hot air it is possible to use other heating, by placing steam coils or electrical heating elements in the tunnel 17, and if necessary similar heating means may be provided also in the free space between the conveyor units, as shown diagrammatically at 17'.

20 Below the horizontal wall 18' of the tunnel 17 an ordinary belt conveyor 16 is placed near the bottom of the drier for carrying the dried material away from the drier. A hopper 16' is arranged below the discharging end of the lowermost strand of the above named conveyors 9, so as to lead the material from these to the conveyor 16.

The operation of my drier is as follows.

25 The material to be dried is placed in the hoppers 12 from which it is fed at a uniform rate of speed on the conveyor plates 9 which carry this material in a direction of the arrow 14 (Fig. 1). Near the end sprocket the plates 9 slide off the end of the guiding bar 10, dumping their contents on the plates below which are lined up on the lower bar 13. This bar 13 extends farther to the right (toward the sprocket) so that there are one or more plates arranged horizontally (or in their operative positions) at the point where the upper plates already hang vertically having dumped their loads.

30 The plates 9 on their return trip over the lower guiding bar 13 carry an evenly distributed load of the drying material, their other sides being turned up. They reach a point at a certain distance from the left sprocket where the bar 13 terminates with its end bent down as shown, allowing the plates 9 to hang freely in a vertical position, dumping their loads down on the plates of the upper strand of the next conveyor below. This operation is then repeated on the second conveyor, and the material is finally dumped on the third conveyor below, and so forth, until the material is finally deposited on the belt 16 which carries it away from the drier.

35 The reloading of the material from one conveyor strand to the other and the stirring or mixing which results therefrom, greatly improve the process of drying, as all the particles are repeatedly and directly exposed to the action of the drying air.

40 The hot air, admitted through the pipe 19,

tunnel 17 and the slot 18, enters the drying chamber and rises to the top between the two units of the conveyors, coming in contact with the material and absorbing the moisture which it contains. The slot 18 is made wider at the end opposite the intake pipe 19 so that the flow of air throughout its length is practically uniform. Cold air entering along the conveyor 16 is heated on the wall 18' before reaching the chains 9.

45 The air is deflected by the vaults 20 and, being more or less saturated with moisture and cooled, descends beyond the conveyors, absorbing more moisture. The air in different portions has different amounts of moisture, and the heavier saturated air, flowing near the side walls, forces the drier and lighter air toward the middle where it meets the rising streams of hot dry air and is carried with it to the top of the drier. Additional steam or electric heaters 17' may be placed at these points to reheat the partly cooled air.

50 With this arrangement the heated air circulates several times from the bottom to the top and around the conveyors until it becomes fully saturated with the moisture from the drying material. A very high economy in fuel results from this arrangement, the capacity of the air to absorb moisture being utilized to the full extent.

55 The slots 22 are made narrower toward the exhaust end, so that the air exhausts at a uniform rate throughout the length of the drier. The heavy saturated air is finally removed through the pipe 23.

60 In Fig. 4 the same apparatus is shown in a modified state especially adapted for drying liquid and semiliquid materials. For this purpose each conveyor chain 3 is opened by extracting one of its link bolts, and some of said chains are united to form a single endless chain conveyor 24 which again is mounted on a plurality of the sprockets 4, of which three remain on their spot, whereas the middle left sprocket is shifted inward, the middle right sprocket is dismantled, and the right bottom sprocket is shifted outward from the drier casing. The guiding bars 10, 13 are also dismantled, and further the conveyor plates 9 are dismantled, and each of them or a special cup or pan is hung up on each chain 3 by aid of two links 25. For this purpose the said sprockets are mounted in shiftable bearings which are not shown, as they may be of any well known construction. The links of the chains 3 have special bores in which as well the fastening bolts of the plates 9 as the hanging bolts of the links 25 can easily be inserted and secured by forelocks or the like.

65 In this condition the plates 9 act as pans, which tend to maintain horizontal position throughout their travel on the chains as shown in Fig. 4. The material may be fed to the conveyor near the right bottom sprocket and

may be removed from it by tilting the pans near the same spot, all outside the casing.

Also in this case the air circulation can be the same as in the first case, and the air can 5 again be circulated automatically and without any additional expenditure of power several times inside of the drier until it becomes fully saturated; also the air is again distributed uniformly throughout the length of the 10 drier.

I claim as my invention:—

In a drier, the combination with a chamber, rows of drying conveyors inside of said chamber, a longitudinal duct for hot gases at the 15 bottom of said chamber, said conveyors forming a central longitudinal clearance for said gases, the roof of said chamber forming longitudinal vaults on top of said conveyors, a central partition between said vaults adapted 20 to deflect said gases to the sides of said chamber, and exhaust ducts at the bottom of said chamber for said gases, said ducts being provided with tapering apertures.

In witness whereof I affix my signature.
25 NICOLAS PANZIREFF.
